US0D1032122S

(12) **United States Design Patent** (10) Patent No.: **US D1,032,122 S**
(45) Date of Patent: ** Jun. 18, 2024

(54) **VACUUM CLEANER**

(71) Applicant: **Xiaojing Bao**, Ruian (CN)

(72) Inventor: **Xiaojing Bao**, Ruian (CN)

(**) Term: **15 Years**

(21) Appl. No.: **29/862,157**

(22) Filed: **Dec. 7, 2022**

(51) LOC (14) Cl. **15-05**

(52) U.S. Cl.

USPC **D32/18**

(57) **CLAIM**

The ornamental design for a vacuum cleaner, as shown and described.

DESCRIPTION

FIG. 1 is a first perspective view of a vacuum cleaner showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded view of the vacuum cleaner thereof. The broken lines shown in the drawings depict portions of the vacuum cleaner that form no part of the claimed design.

1 Claim, 9 Drawing Sheets
